ABSTRACT: This invention pertains to a medical drape, adapted to provide a sterile field for performing a catheterization procedure and other medical and surgical procedures. Another feature covered herein is a novel method of performing the catheterization procedure using the new drape. As a secondary feature, the drape also serves as a wrapping for storing the medical and surgical equipment in a sterile field prior to performance of the procedure. The drape, adapted to be draped over the patient, comprises a sterilizable, foldable sheet of material having an opening formed therein through which the procedure is performed and having graspable means disposed thereon for unfolding the material without contaminating the sterile field.

CATHETER DRAPE AND WRAP

BACKGROUND OF THE INVENTION

1. Field of the Invention

This invention relates generally to a medical drape or shield and a medical supply and more particularly to a catheter drape for maintaining a sterile field, which also serves as a wrap for containing a tray that holds the equipment used in performing the catheterization or other surgical or medical procedure in a sterile field.

2. Description of the Prior Art

The catheter drape is a medical supply used to provide a sterile field for the catheterization procedure. The equipment required to perform the catheterization procedure normally includes one or more drapes; a pair of powdered, cuffed, disposable gloves; a towel; an antiseptic; sponges or cotton balls; a lubricant, a catheter, a tube and a collection bag; and a specimen bottle. This equipment can be provided in a sterile package by a medical supply house or assembled, packaged and sterilized by the doctor or hospital.

The present method of preparing a hospitalized patient and performing the catheterization procedure includes the following steps: obtaining the sterilized equipment, as described hereinabove; placing a screen or partition around the bed of the patient to insure privacy for the patient; instructing the patient concerning the procedure; positioning the patient; uncovering the patient; draping the patient's abdomen with a bath blanket; placing the catheter equipment package at the foot of the bed between the legs of the patient; unwrapping the equipment; donning the sterilized gloves, placing one of the sterilized drapes over the abdomen of the patient; placing another of the sterilized drapes under the hips and between the legs of the patient, two drapes may be used for this purpose; cleansing the patient; lubricating the catheter; catheterizing the patient; removing the catheter, the drapes and the bath blanket; recovering the patient; removing the screen; disposing of the contaminated materials; and recording the entire procedure.

Commercially available, sterile disposable catheterization trays are normally packed with the gloves on top of the equipment in the tray, thus assuring that the above procedure is followed.

The conventional procedure, hereinabove described, often results in a contaminated field because the gloves are donned before draping. As the patient is draped, the sterilized gloves on the hands of the nurse can easily contact the patient and may become contaminated. The legs and rectal area of the patient are exposed, thus both depriving the patient of maximum privacy and allowing for possible contamination in the event that either the gloves or equipment come in contact therewith. In event of any of the equipment is dropped, it will more than likely contact a nonsterilized area of the patient or bed.

The conventional method also requires unnecessary steps and equipment, in that the screen is not necessary if the patient's body is not exposed, the novel drape of this invention can be used in place of two or three drapes under the old method and the patient's privacy and a sterile field can be assured. Furthermore, the procedure can be accomplished more gracefully and efficiently with positive asepsis by utilization of the method and drape hereinafter described.

The utilization of the novel drape of this invention provides coverage and privacy of all exposed parts of the patient, and maintains a sterile field in those areas in which the equipment is held and in those areas in which the equipment may contact or fall during the procedure.

For example, a disposable surgical drape, as described in U.S. Pat. No. 3,137,387, provides an opening therein through which the medical or surgical procedure can be performed, however, due to its construction, only the inner areas of the thighs are covered, leaving part of the patient exposed. In draping the patient, both sides of the drape must be touched before sterile gloves are donned, thus contaminating the sterile field and furthermore, more than one layer of material

must be used as a pocket is provided therein, thus adding to the complexity of the drape, the cost of manufacture, and substantially reducing the simplicity and ease of manufacture. Furthermore, pockets and multiple layers of material affect the adaptability of the drape as to resterilization and reuse.

SUMMARY

In summary, this invention is a drape for medical and surgical procedures comprising a rectangular, foldable sheet of material adapted to completely cover the abdomen and legs of the patient and the area of the bed between the legs of the patient, thus providing a sterile field. The material has an opening formed off center therein, which provides an entry through which the procedure can be performed yet provides minimum exposure of the patient and a maximum field of sterility. Graspable means are disposed on one side thereof, opposite the side required to be kept sterile, for positioning the drape. The drape also, as a secondary feature, serves as a wrap or package for containing the sterile equipment required for the procedure.

Furthermore, utilization of this drape substantially reduces the number of drapes required to maintain a sterile field and protects the privacy of the patient, thus providing a new and simpler method of preparing the patient and performing the medical or surgical procedure.

It is therefore an object of this invention to provide a novel medical and surgical drape.

Another object of this invention is the provision of a drape which completely covers all exposed areas of a patient.

A further object of this invention is to provide a drape which can be unfolded without contaminating one side thereof.

Yet another object of this invention is the provision of a drape having an opening formed therein through which a surgical or medical procedure can be performed.

Yet another object of this invention is the provision of a drape which is adapted to serve as a wrapper for the equipment which is used for performing the medical or surgical procedure in which the drape is used for maintaining a sterile field.

Still another object of this invention is the provision of a drape which provides a sterile field in all areas that an instrument might contact in event the doctor or nurse should drop same.

Still a further object of this invention is the provision of a drape which is draped over a patient before sterile gloves are donned by the nurse or doctor.

Another object of this invention is the provision of a method of performing a catheterization procedure.

Still another object of this invention is the provision of a drape which substantially reduces the length of time required to drape a patient, for a surgical or medical procedure, furthermore the number of steps required to perform the procedure are reduced, only one drape is required, asepsis is provided, exposure of the patient is substantially eliminated, and the procedure is more gracefully and efficiently accomplished.

Yet another object of this invention is the provision of a drape which is extremely simple in construction, effective in use; economical to manufacture, and adapted for resterilization and reuse.

BRIEF DESCRIPTION OF THE DRAWINGS

In the drawings, as hereinbelow described, a preferred embodiment of the invention is shown, however various modifications and alternate constructions can be made thereto without departing from the true spirit and scope of the invention as defined in the appended claims.

FIG. 1 is a perspective view of the drape of this invention in a folded condition;

FIG. 2 is a top plan view of a partially unfolded drape at a particular step in the unfolding process;

FIG. 3 is a top plan view showing one side partially unfolded;

FIG. 4 is a top plan view showing both sides partially unfolded; and

FIG. 5 is a top plan view showing the drape completely unfolded.

DESCRIPTION OF THE PREFERRED EMBODIMENT

Referring now to the drawings, the catheter drape of this invention is indicated generally at 10 in FIG. 5. The drape 10 is formed from a rectangular foldable sheet of material having an upper side 11 and a lower side 12 (FIG. 1). A rectangular opening 13 is formed in the drape 10 offcenter of the center thereof with the edges of the opening disposed parallel with the corresponding edges of the drape, as best noted in FIG. 5. Secured to the lower side 12 near each corner of the drape are graspable tabs 14 (FIGS. 1-4) or flaps. An equipment tray 16 (FIG. 5) is removably disposed on the top side 11.

A plurality of parallel fold lines 17 through 27 (FIG. 5), extending diagonally to the edges of the drape 10, divide the drape into a plurality of horizontally disposed panels 28 through 39. The first fold line 17 is disposed substantially adjacent the top corner 15 of the drape, while the fold line 27 is disposed near the bottom corner 40 of the drape. A second set of fold lines 42, near the left corner 41, through 47, near the right corner 48, extending perpendicular to the horizontal fold lines, divides the drape into a plurality of vertically disposed panels 52 through 58.

The equipment tray 16 holds the equipment (not shown) normally required for a particular medical or surgical procedure. In the catheterization procedure utilizing the drape of this invention, the equipment would consist of a catheter, a tube, a collection bag, an antiseptic, sponges or cotton balls, forceps, a lubricant, a specimen bottle and a pair of powdered, disposable gloves. Prior to the performance of the catheterization procedure, the equipment must be collected, placed in the tray, wrapped in the drape and sterilized.

To wrap the equipment tray in the drape, the following procedure is followed:

The drape is placed on a table with the top side 11 facing up;

The equipment tray 16 is placed on the drape on the panel 37-55, near the lower corner as viewed in FIG. 5;

The drape is grasped at the fold line 24 and folded over the top of the tray with the panel 36-55 on top of the tray and the panel 35-55 on top of the panel 36-55;

The fold line 22 is then grasped and folded over the tray with the panel 34-55, having the opening 13 therein, on top of the panel 35-55 and the panel 33-55 on top of the panel 34-55;

The fold line 20 is then grasped and folded over with the panel 32-55 on top of the panel 33-55 and the panel 31-55 on top of the panel 32-55;

The panel 30-55 is then folded over the panel 31-55 by folding at the fold line 19;

The drape is then folded at the fold lines 18 and 17 thus forming the drape, as viewed in FIG. 4, with the tab 14 on the top end of the drape projecting upwardly therefrom;

The left corner, as viewed in FIG. 4, is grasped and the drape folded in accordion folds, starting at fold line 44, over the tray with the tab 14 on the left corner partially projecting upwardly as viewed in FIG. 3;

The right corner (FIG. 3) is folded over the tray in accordion folds, starting at the fold line 45, with the tab 14 on the right corner partially projecting upwardly as viewed in FIG. 2;

The bottom corner (FIG. 2) is folded over the tray with the panel 38-55 disposed over the tray and with the triangular panel 39-55 folded around the tray and disposed under the tray in juxtaposition with the panel 37-55, thus as viewed in FIG. 1 the tray is actually upside down.

Upon completing the folding and wrapping procedure, the drape and equipment contained therein are sterilized. If

desired, the complete unit can be placed in an outer wrapper, however this step is unnecessary, as only the bottom side 12 of the drape is exposed to the exterior thus maintaining a sterile field for the top side 11 of the drape 10 and the equipment 5 contained therein.

It is to be noted that the fold lines depicted in FIG. 5 are determined by the size of the tray, thus for different sized trays the fold lines will vary in number and location. However, it is necessary that the last fold for each corner must be provided 10 to allow part of or all of the tab 14 thereon to be disposed on top to allow it to be grasped without touching any portion of the top side 11 of the drape 10.

The procedure to be followed in performing a catheterization on a patient utilizing the novel drape of this invention is as 15 follows: obtaining the sterilized equipment wrapped in the drape 10 as described hereinabove; instructing the patient concerning the procedure; positioning the patient; uncovering the patient; placing the sterilized package between the legs of the patient at substantially the foot of the bed; grasping the tab

20 14 near the bottom corner 40 and partially unfolding the bottom portion of the drape by disposing the bottom corner at the foot of the bed; grasping the tab 14 near the right hand corner 48 and unfolding the right portion of the drape across the right leg of the patient and completely covering same; grasping the tab 14 near the left corner 41 and unfolding the left portion of the drape across the left leg of the patient and completely covering same; grasping the tab 14 near the top corner 15 and unfolding the top portion of the drape across the abdomen of the patient; positioning the drape by grasping one of the tabs

25 and sliding the drape to a position wherein the area to be operated on is directly under the opening 13; donning the sterilized gloves; cleansing the patient; lubricating the catheter, catheterizing the patient; removing the catheter and the drape; recovering the patient, and recording the entire procedure.

The above procedure of draping the patient is accomplished without touching the sterile or upper side 11 of the drape 10 because only the lower side 12 and the tabs 14 are touched by 40 the nurse or doctor. Furthermore, the sterile gloves are not donned until the draping procedure is completed. It will be noted that, by placing the drape diagonally on the patient, all uncovered areas of the patient are draped and only the sterile portion of the drape can be contacted by the nurse or the equipment. This latter feature saves considerable time for the 45 nurse, because if a sterile item is dropped it will land in the field of operation which is sterile, thus preventing lost time in replacing or obtaining new sterile equipment or items.

This drape, in addition to being adapted for use in the 50 catheterization procedure, can also be used for vaginal examinations, spontaneous abortions, papanicolaou smears, rectal and lower colon examinations and other similar type procedures.

Although a preferred embodiment of this invention has 55 been described and disclosed hereinabove, it is to be remembered that various modifications and alternate constructions can be made thereto without departing from the true spirit and scope of the invention as defined in the appended claims.

I claim:

60 1. A drape for covering a patient during a medical procedure to provide a sterile operating field comprising: a foldable, sterilizable sheet of sufficient size to substantially cover the patient, having an upper side and a lower side, said sheet having an opening formed therein through which the procedure is performed; and four elongated graspable tabs, each secured to said sheet lower side inwardly of a corner thereof, wherein said tabs lie flat against said sheet and do not extend outwardly of the edges of said sheet.

65 2. A drape as defined in claim 1 wherein said tabs are secured on both ends thereof to said sheet lower side.

70 3. A drape as defined in claim 2 wherein said sheet is folded in accordion folds from each corner toward the center with the last fold of each corner disposed with said tab disposed outwardly to allow it to be grasped without touching any portion of said sheet upper side.

3,542,019

5

4. A drape as defined in claim 3 wherein said sheet is rectangular in shape and adapted to be diagonally disposed over the

6

patient and said opening is rectangular with the edges thereof disposed parallel with the corresponding edges of said sheet.
